United States Patent Office

Des. 197,599
Patented Mar. 3, 1964

197,599

CHAIR OR SIMILAR ARTICLE

John E. Moore, Gloucester, and Aubrey A. Ramsey,
Dutton, Va.

Filed June 14, 1962, Ser. No. 70,552

Term of patent 14 years

(Cl. D15—1)

Fig. 1.

Fig. 2.

*Fig. 3.**Fig. 4.*FIGURE 1 is a side elevational view of a chair or similar article showing our new design;

FIGURE 2 is a front view of the chair;

FIGURE 3 is a top plan view thereof; and

FIGURE 4 is a back view of the chair.

The dotted lines indicate that the chair is of indeterminate width.

We claim:

The ornamental design for a chair or similar article, as shown and described.
